INCLINED PLATE AMALGAMATOR

Edward F. McTarnahan, Seattle, Wash.

Application September 23, 1946, Serial No. 698,764

2 Claims. (Cl. 209—54)

1

This invention relates to apparatus for collecting particles of gold and silver from finely crushed rocks and the like; and particularly such apparatus with passageways for such rock when crushed to travel therethrough in oppositely disposed flumes.

In the process of collecting fine particles of gold and silver from crushed rock and sand and the like it is important that the material be carried in a water solution over surfaces covered with mercury for amalgamating together with the particles of gold and silver. It is also important that such passageways and surfaces shall continue in relatively long distances for collecting all of such particles, and where such longitudinal distances are not available in a continuous line it is important that the same length for such surfaces be arranged within a relatively small surface area.

It is therefore an object of this invention to provide a plurality of flumes each relatively short in itself but connected with one or more others will provide a passageway by rotation through the series of flumes by gravity. It is a further object to provide in such flumes a series of smooth plates covered with mercury over which the solution of pulverized rock and water will flow downward for collecting gold and silver by amalgamation with the mercury; and further to provide at the lower end for the last one of a series of flumes a catch basin to gather any of the particularly light particles which may have failed to connect over the plates.

With these and other objects to be hereinafter stated I have illustratively exemplified my invention by the accompanying drawings of which:

Figure 1 is a top plan view of two flumes operatively connected together. Figure 2 is a vertical side elevation of the flume shown in Fig. 1, with portions in section. Figure 3 is an enlarged detail view of a portion of a side wall of one of the flumes shown in Fig. 2, with plates in section. Figure 4 is an end view of the two flumes suspended by a frame. Figure 5 is an enlarged detail fragmentary view showing two side walls and one of the plates in section, taken on line 5—5 of Fig. 3. Figure 6 is a perspective plan view of one of the curved plates from the flume. Figure 7 is an enlarged detail fragmentary cross section view of one of the plates with a silver plating thereon and a film of mercury thereover. Figure 8 is an enlarged detail fragmentary view of the adjacent ends of two flumes and a conduit connecting the flumes.

Like characters on the different figures represent like parts. The Letters A and B respectively represent a pair of flumes for receiving and conducting finely crushed rock and the like containing particles of gold and silver, all in a water solution. The top or head end 10 of A, is supported at a determined elevation by a frame work 11 and

2

a yoke 12. The yoke carries a threaded eye bolt 13 on the lower end of which is a nut 14 by which the elevation of the head of the flume may be adjusted for varying the degree of slope desired for the flume to facilitate the flow of the solution therein.

Obliquely across the inside of the walls 15—16 are affixed a series of cleats 17 spaced apart for supporting flat amalgamator plates 18 across the flume on suitable slight decline from the head of the flume, sufficient to facilitate the flow of water and crushed rock and metal particles thereover. At the outer ends of the cleats are flanges 19 to prevent the flat plates from shifting outward while in operation, but over which the plates may be readily moved manually.

The plates are of dimensions to extend laterally from wall to wall and outward a suitable distance for the flow thereover. The plates are preferably formed from what is known as "Muntz" metal, or copper or other suitable metal which will not tarnish or rust and will maintain a smooth surface, and these are preferably reinforced by ribs beneath, not shown, to prevent sagging thereof. Before use, the top surfaces are coated with a fixed sheet silver plating 20 to assure a smooth surface and to facilitate removal therefrom of congealed amalgam with silver and gold particles. Over the silvered plating is spread a film or coat of mercury indicated as 21 in Fig. 7 which normally remains in such position being slightly attracted by the silver plating; but when particles of silver or gold in the solution flow over such mercury, the mercury and such particles of gold and silver combine into an amalgamated mass which slightly adheres to the silver plating.

Alternately between the cleats 17 in spaced relation between the same are additional cleats 22 affixed to the walls of the flumes for supporting additional amalgamator plates 23 which are constructed with silver coating and mercury in like manner as described for the flat plates 18; but are further extended outward beyond the front edges of the flat plates and their outer edges are curved upward for baffles 24 to catch and stop the overflow of a solution from the flat plates above and to direct the flow thereof inward or backward toward the bottom 25 of the flume. The rear corners of the curved plates are provided with legs 26 leaving spaces 27 for passageways for the down flow of the solution to the next flat plate beneath the same. The two sets of cleats are relatively disposed in oblique positions across the inner walls of the flume in order to support the plates, when the head of the flume is elevated to the desired position, in relatively inclined positions with the degrees of slope downward and outward from the bottom of the flume to facilitate the flow by gravity thereover, of the solution. These degrees of slope may be changed as desired

for various densities and weights of the solids in the solution. The elevation of the head of the flume will increase the slope of the flat plates and lessen the slope of the alternate curved plates, therefore the cleats for supporting the curved plates are given a greater degree of slope inward and downward than the slope given for the flat plates, thus providing a sufficient slope for the curved plates for conducting the solution inward even after the head of the flume has been elevated a greater degree than indicated in the drawings.

The flume B is provided with similar sets of flat and curved plates as described for the flume A. The head end of flume B is supported by similar yoke and eye bolt as for flume A and alongside of the lower end or tail of flume A and connected therewith by a conduit or short tube 28 for passageway for the solution from the lower end of A into the head end of B to provide continuous travel for the solution rotating through A and B over the plates described. The conduit carries a thread 33 which meshes in the side wall 15' of flume B and so permits sufficient rotation to provide adjustment of the elevations and slopes of the flumes. The other end of the conduit is connected with the lower end of the flume A and may be held thereto in any suitable manner as by any spot weld indicated by 34 to a reinforcing strip 35 which is attached to the floor 25. At the base or tail end of B is provided a catch basin 29 for trapping any light weight particles of gold or silver that may have escaped capture on the plates. An exit with the cap 30 at one end of the basin facilitates the removal of the contents of the basin.

The flume B as shown in the drawings is disposed in a sloping direction in reverse to the flume A but parallel with each other so that the two flumes require an area for operation no longer than either one flume might require alone, but the length of travel provided for the flow of the solution is approximately four times the length of either flume, for the reason that the flow forward and back on the flat and curved plates in each flume doubles the length of travel therein, which is again doubled by the two flumes, thus facilitating the use of the flumes in a relatively small area.

In practice it is advisable to provide duplicate sets of both kinds of plates for each flume so that when necessary to remove any of the plates when suitably covered with the amalgamated mercury and silver and gold such plates may be removed while the flow of the solution is continuing and clean plates inserted in their stead. It is also advisable to provide suitable tanks of water into which the amalgamated covered plates may be immersed until the operator desires to remove the amalgam therefrom. Such removal of the amalgam is facilitated by the use of rubber or other brushes which will not injure the silver coating on the plates. Such amalgam may be then reduced and the particles of gold and silver and mercury separated by the ordinary processes.

In operation the pulverized rock and sand is deposited from any milling operation or otherwise in proper quantities on the topmost flat plate in flume A and liquified by and a suitable quantity of water supplied through the pipe 31, and

thence the fluid solution flows over and from the several flat plates falling from the outer edges thereof and splashing down upon the outer portions of the curved plates whereby the solids in the solution are broken up to facilitate the removal therefrom of the particles of silver and gold.

Having described my invention I claim as new for Letters Patent:

1. An apparatus for collecting gold and silver from crushed rock and the like, comprising, a flume having side walls and bottom, a frame for supporting the head end of the flume on a slope from the bottom end, adjustable means connected between the frame and head of the flume for varying the degrees of slope thereof, cleats attached obliquely across the insides of the walls of the flume in spaced relation one above the other for supporting flat amalgamator plates on suitable angles across the flume to facilitate the flow of liquid solution of crushed rock and particles of gold and silver thereon, flat amalgamator plates disposed across the flume and over respective pairs of cleats at the ends thereof for supporting and guiding such solution, additional cleats attached to the walls of the flume between said first described cleats and in spaced relation therefrom for supporting alternate plates, additional amalgamator plates having their outer edges extended beyond the outer edges of the flat plates and being turned upward for baffles for reversing the flow of solution backward toward the floor of the flume and having passageway through the inner edges of the curved plates for the flow of the solution to the successive flat plate beneath, a silver plating mounted on the upper faces of all such plates for assuring smoothness thereof and to prevent the loss of mercury therefrom, a coat of mercury spread over the face of a silver plating for attracting and amalgamating with particles of gold and silver from the solution.

2. A structure described in the foregoing claim 1, together with a second flume having similarly constructed and disposed plates, the head end of the second flume being elevated higher than the tail thereof and mounted along side the tail end of the first flume, a tubular duct for adjustably connecting the flumes at their juxtaposition and for conveying solution from the tail of the first flume to the head of the second flume, a trough across the tail of the second flume for gathering light particles of gold and silver that have failed to amalgamate on the plates, said flumes being disposed in parallel lines with the tail of the second flume opposite to and lower than the head of the first flume to conserve space and provide relatively long distance travel for the solution over the multiple sets of plates inside of a relatively short longitudinal space.
